ELECTRIC FLUID HEATER

Robert A. Carleton, Brooklyn, N. Y., assignor to
 National Electric Heating Company, Inc., New
 York, N. Y., a corporation of New Jersey

Application August 7, 1931, Serial No. 555,801

8 Claims. (Cl. 219—38)

This invention relates to improvements in electric fluid heating apparatus of the type in which the fluid is heated by direct contact with the heating elements.

- 5 In electric heaters great difficulty has been encountered in obtaining rapid heating and the heaters heretofore used have been of low efficiency and rather prone to get out of order and need adjustment and repairs.
- 10 The object of this invention is therefore to provide an electric fluid heater which will operate both rapidly and efficiently and which is of a sufficiently rugged construction so that it will not easily get out of order.

- 15 It is the further object of this invention to provide a heater of this type which will operate either on direct current or on alternating current having any of the usual characteristics and which will be adaptable for both domestic and industrial use.

20 With these objects in mind, heating elements have been devised which have the form of thin, closely-spaced ribbons of metal having a high electrical resistance, and a plurality of these elements are held edgewise between supports to form heating units. A series of these heating units are mounted for use in parallel relation and electrically connected so that the current flows through the alternate units in opposite directions. The heater is supported within a tank where the fluid is caused to circulate between the closely spaced ribbons from which it is heated.

25 By the closely spaced, thin ribbons between which the fluid is caused to flow a very high rate of heat transfer is accomplished and large amount of current may be passed through the heating elements and rapid heating of the fluid may take place. By arranging the units which make up the heater so that the current flows in opposite directions through adjacent units the self-induction in the heating units is neutralized and the power factor and hence the efficiency of the device greatly increased. By clamping the thin ribbons edgewise between supports, they are held rigidly in position and this coupled with the structure which will be further described produces an electric fluid heater which is exceptionally rugged and has little tendency to get out of order or need adjustment.

30 In order that the temperature to which the fluid is heated may be accurately controlled, it has been found desirable to control the amount of current which flows through the heating elements by use of a thermostat operated in accordance with the temperature of the heated fluid. It has

also been found desirable to incorporate a safety switch which will stop the flow of current to the heating units in case the amount of fluid in the heater drops below a predetermined minimum.

35 In constructing the heater, it has been found that non-corrosive metals may very advantageously be employed to prevent the fluid being treated from damaging the heater. When so constructed there is practically nothing in the device which is subject to deterioration or breakage or which is liable to get out of adjustment.

40 It will thus be apparent that the heater as constructed according to this invention will possess all those qualities of efficiency, durability, speed and automatic control which are desirable.

45 For a more detailed description of the apparatus of this invention, reference may be had to the appended drawings and the description thereof.

50 In the drawings, Figure 1 is a plan view in section of the apparatus.

55 Figure 2 is an elevational view of the heater in section taken on the line 2—2 of Figure 1 and this view shows the electrical connections to the heater.

60 Figure 3 is an enlarged sectional elevation of the heater units.

65 Figure 4 is a detailed sectional view of a part of the heater units showing the method of supporting the ribbons; and

70 Figure 5 is a plan view of the section shown in Figure 4.

75 Figure 6 is a sectional elevation of a circulating fluid heater embodying the principles of this invention.

80 Figure 7 is a sectional view of the device shown in Figure 6, taken on the line 7—7.

85 Figure 8 is a sectional view of the device shown in Figure 6 taken on the line 8—8.

90 Figures 9 and 10 are sectional detail views of the device of Figure 6 on an enlarged scale.

95 As illustrated in Figures 1 to 5 of the drawings, one of the preferred constructions employing the principles of this invention is a fluid heater in which the fluid is circulated through the heater by the convection currents set up by the heating units. The heater comprises a tank made up of an inner shell 21 suspended within an outer shell 22 and insulated therefrom by insulating material 23. The inner shell is preferably of some non-corrosive metal such as Monel metal, copper, or the like; while the outer shell 22 is usually of sheet steel. The insulating material may be any of the well known materials such as asbestos, diatomaceous earth, min-

eral wool or the like. The fluid enters the tank through an inlet 24 and leaves through an outlet 25. The top of the tank is open but is covered by a hood 26 from which fumes and vapors 5 are exhausted through an outlet 27.

A heating device 28 is suspended within the tank near the bottom thereof by means of metal strips 29 which are supported from a ring 30 near the top of the tank. The ring 30 is received 10 in slots in lugs 31 which are welded or otherwise suitably fastened to the inner wall of the tank near the top thereof. Bolts 32 hold the ring 30 tightly in place.

The heating device comprises a plurality of 15 heating units each consisting of a thin metal ribbon formed into a closely spaced spiral 33. The spirals 33 are secured rigidly in place by being clamped edgewise between radially extending insulating plates 34. Each of the insulating plates 20 34 is provided with a plurality of grooves 35 which receive the edges of the spiral ribbons. The radial insulating plates 34 may be of any suitable insulating material such as slate or porcelain. The outer insulating plates have grooves 25 only on their inner edges but the insulating plates between adjacent spirals of metal ribbon have grooves on the opposite edges and the assistance of supporting two of the spirals.

The insulating plates 34 are supported by 30 radially extending arms 36 to which they are attached by the bolts 37. The radial extending arms 36 are all secured to a frame member 38 which extends axially of the spirals at the center thereof. Bolts 39 are used to secure the radial arms 36 to the frame member 38.

Each group of parallel radial arms 38 are secured together at their outer ends by a bar 40 to which they are bolted by the bolts 41. The bars 40 are parallel to the frame member 38 and 40 are all attached at their upper ends to a ring-shaped strip 42 by means of angle brackets 43 which are bolted to the bars 40 by bolts 41 which secure the radial arms to the bars 40 and bolts 44 by which the angle brackets are fastened to 45 the ring 42. The bottom ends of the bars 40 are similarly connected to a ring-shaped strip 45 and the ring-shaped strips 42 and 45 are in turn bolted or otherwise suitably connected to the supporting strips 29.

The inner ends of the spirals 33 are all connected together by a connector strip 46, and the outer ends of the spirals are each separately connected to the source of current supply. These connections are made by means of connecting strips 50 which connect detachably to connecting strips 51 at a connection block 52 which is supported adjacent the units by a supporting member 53 suitably attached to the rings 42 and 45. The connecting strips 51 connect 55 to insulated connecting bolts 49 which extend through insulated and oil tight bushings in the tank wall. Current is supplied to the connecting bolts 49 outside of the tank to energize the heating units.

In the device shown, there are three heating units and the heater is operated on a three-phase electric current. This current is supplied from a supply line 54 through a main switch 55 and a magnetically operated switch 56 but may alternatively be supplied through the main switch 55 and auto-transformer 57 and a magnetically operated switch 58. The switches 56 and 58 are so connected that only one of the switches may be closed at a time and the heater units are supplied with current through either one or the other

of the switches. Current to operate the magnetic switches is taken from the main line below the main switch 55 by a pair of wires 60 and 60a. The wires 60 and 60a are connected to a hand operated switch 61 which may break the circuit and thereby allow the magnetic switches to open and the main circuit to be broken. From the hand operated switch 61 the wires 60 lead to a float operated switch 62 which has a float 62' inside the tank and operates to break the circuit if the fluid level in the tank falls below a predetermined minimum. From this switch the wire 60 leads to a thermostatic switch 63 which has a heat sensitive element 64 extending into the tank and which operates to break the circuit if the 15 temperature in the tank exceeds a predetermined maximum. From this switch the wire 60 leads to a thermostatic control switch 65 having a heat sensitive element 66 extending into the tank, and operating to selectively connect the wire 20 60 to either the wire 67 which leads to the magnet of the switch 56 or the wire 68 which leads to the magnet of the switch 58. The thermostatic control switch 65 operates so that it opens the switch 56 and closes the switch 58 when the temperature reaches a predetermined maximum and reverses the operation when the temperature reaches a predetermined minimum, thus tending to keep the fluid in the tank at a fixed temperature.

In the circulating fluid heater as illustrated in Figures 6 to 10, the device comprises a tank 70 preferably of non-corrosive metal surrounded by a casing 71 of sheet metal or the like and having insulation material 72 between the tank and the sheet metal casing. The tank is provided with an inlet 73 and an outlet 74 and is closed both at the top and at the bottom so that liquid may be forced to circulate therethrough under the pressure of a pump or similar circulating 40 device. As in Figures 1 to 6, the heating units 33 are in the form of closely spaced spirals of metal ribbon held edgewise between radially extending insulating plates 34 which are in turn bolted to radially extending supporting arms. 45

A frame 75 having radially extending supporting arms 76 is mounted on a rod 77 which extends axially of the spirals, the insulating plates 34 are fastened to the radially extending arms by means of bolts 78 and the frames 75 are spaced 50 along the rod 77 by means of collars 79 which surround the shaft 77 between the frames. The ends of the rod 77 are threaded to receive nuts 79 which hold the frames in a spaced position upon the rod. The block 80 is bolted to the outer end of each of the radial arms 76 and rods 81 extend through the blocks 80 and are surrounded by collars 82 which space the blocks along the rod. Each of the rods 80 is also threaded at its ends to receive nuts 83 which hold the blocks and collars in position thereon.

A flat ring 85 lies on top of each set of blocks which are in the same horizontal plane and prevents the flow of fluid around the sides of the heating units. The rings 85 are cut out to surround the rods 81 and are clamped between the collars 82 and the blocks 80. Perforated plates 86 lie both above and below the heating device and are held in place by means of supporting strips suitably fastened thereto as by welding. 70 The supporting strips are cut out to fit around the rod 81 and are held between the blocks 80 and the nuts 83 at the top and at the bottom of the heating device.

The heating device is held in place in the tank 75

by means of brackets 90 which are held on the top of the rods 80 by the nuts 83 and bolted to the sides of the tank 70 by bolts 91.

Conducting strips 93 connect to the outer ends 5 of a part of the spirals and connecting strips 94 connect the inner ends of a part of the spirals together. The connecting strips 93 extend through spacers 95 supported from the radially extending supporting arms and are suitably insulated therefrom by insulators 96. These connecting strips 92 connect with insulated bolts 97 which pass through the wall of the tank and are connected on the outside with a suitable source of electric current.

15 As shown in the drawings, the connections 93 and 94 are so arranged that the heating spirals are connected in three series of four spirals each, and each of the series is connected across one phase of a three-phase alternating current which 20 is supplied from a supply line 98 through a magnetic switch 99.

The magnetic switch 99 is controlled by a circuit 100 which receives its power from the main supply line 98 and may be broken by either a thermostatic switch 101 operated by a heat sensitive element 102 near the outlet of the heater or by a switch 103 which is connected to the intake of the heater and operates to break the circuit upon substantial cessation of the flow of fluid to the 30 heater. This circuit may also be broken by a hand operated switch 104 and when broken by any of these switches the magnetic switch is opened to stop the flow of current to the heater. This prevents the flow of current to the heater 35 when the fluid in the heater becomes too hot or ceases to flow and thus prevents damage to the fluid or the heater.

It will be apparent from the foregoing description that the fluid flowing through the heater will 40 be caused to flow through the relatively small spaces between the metallic ribbons and will thus be subjected to the heating effect of a large surface over which the fluid will pass in relatively small streams.

45 It may also be observed that the heating elements being of light material and in direct contact with the liquid will cool quickly if the current is shut off and the apparatus may therefore be very finely controlled to give a very accurate 50 temperature adjustment.

The apparatus of this invention is useful for any kind of fluid heating, but the apparatus of Figures 1 to 6 is particularly adapted to heating and bodying or polymerizing linseed or similar oils. When bodying such oils, the oil is heated to a selected temperature usually within the range of 560 to 625° F and maintained at the selected temperature for a period of time necessary for the desired bodying or polymerizing 55 action to take place which may require from one to ten hours or more, depending upon the kind or quality of the oil, the temperature at which it is treated and the body or viscosity required.

When heated to a certain temperature, which 60 may vary with different oils, but is usually between 560 to 575° F, an exothermic reaction takes place within the oil, causing a relatively rapid rise in temperature, the degree and rate of temperature rise depending somewhat upon the rate 65 or speed the oil has been heated, the slower the rate of heat input at the critical temperature, the less the temperature rise due to the exothermic reaction.

When the oil is heated to or near its critical or 70 reaction temperature, a relatively slight increase

in temperature will cause cracking or breakdown of the oil molecules to take place, converting part of the oil into free fatty acids, carbon and other compounds that injuriously effect the quality of the finished oil and reduces its value for the purpose intended. It is therefore very important that the heating apparatus in which the oil is heated be closely controlled and quickly responsive to changes in temperature of the oil.

10 In usual constructions, the oil is heated in open portable kettles of one to two hundred gallon capacity, wheeled over open fires of coal or coke, and the usual means of controlling the temperature of the oil is for the attendant to withdraw the kettle from the fire should the oil become too hot and replace the kettle as it becomes too cool, under which conditions the temperature regulation is poor, the temperature of the oil varying in some instances 30° F. or more. Larger size 15 kettles are sometimes used, in which event they are installed permanently in brick settings and heated by means of coke or oil fires.

20 During the heating operation the layer of oil in contact with the kettle bottom, the underside of which is exposed to a furnace combustion temperature of 2400° F. or more, is overheated and cracked or decomposed, increasing the loss due to oil fumes and vapors, increasing the fatty acid content and causing darkening of the oil.

25 As stated, it is desirable to heat the oil in a regular and uniform manner, avoiding the use of highly heated surfaces, and to maintain the oil at a regular and uniform temperature throughout the period of time required to obtain the desired bodying reaction.

30 In the apparatus illustrated in Figures 1 and 2, the heating elements comprising the relatively thin ribbons closely spaced apart in the form of concentric spirals, presents the greatest possible heating surface area, uniformly distributed in the 35 fluid in the receptacle, and due to the thermosiphonic action of the hot oil rising through and between and in direct contact with the heating surfaces comprising the spirals of the heating element, creates a vigorous circulation, providing the maximum heat transfer rate and the minimum temperature differential between the heating surfaces and the oil in contact therewith.

35 Due to the relatively small mass or weight of the high resistance metallic ribbons comprising the heating elements, and the relatively small temperature differential between the heating surfaces and the oil, the amount of heat stored in the heating elements and given off after the electric heating current is interrupted is negligible, and due to the sensitive and close automatic operation of the thermostatic device, the body of oil under treatment may readily be kept within 1° F. of the desired determinate temperature.

40 The speed or rate of heat absorption of the oil depends upon the following approximate conditions: 1st, directly as the temperature difference between the heating surfaces and the oil; 2nd, as the one half power of the velocity; and 3rd, 45 as the reciprocal of the square of the distance the heat is transmitted or the distance between the heating surfaces. Of the three main conditions influencing the rate of heat absorption, the second and third are the more important. The 50 following example will illustrate the advantage of the arrangement of the heating element as shown in Figures 1 and 2, of the present invention.

Assuming a 1000 gallon oil fired oil bodying 55

kettle, having a diameter of 66 inches and a height of 110 inches, the oil filling the kettle to a height of 66 inches from the bottom, the heat being applied to the kettle bottom and for a distance of 12 inches up the sides, providing a total area of 5840 square inches of heating surface. The heat must be transmitted from the bottom and lower sides of the kettle to the centre of the mass of oil, or to a distance of approximately 40 inches.

The heater which is the subject of this invention would be a kettle of the same dimensions as above, the electric heating element consisting of the high resistance metallic ribbon, four inches wide and 172 feet long, in a concentric spiral form with the adjacent turns of the spirals $\frac{3}{4}$ of an inch apart, three such heating elements being used and connected to a polyphase electric circuit, providing a total heating surface area of 49,500 square inches, uniformly distributed through the mass of oil in the kettle. Due to the vertical spacing of the heating elements presenting both sides of the ribbons as the heating surfaces with which the oil is in direct contact, there is a vigorous circulation of the oil created up through the said spirals and down the sides of the kettle between the outer turns of the spirals and the side walls of the kettle, which readily absorbs the heat generated in the heating elements, tending to cool them and permitting the use of a relatively high rate of heat input per unit area of heating surface.

The greater rate of heat absorption, due to the close spacing of the heating elements or spirals of high resistance ribbons, as compared to the direct fired kettle heated by oil mentioned above is illustrated by the following example:

Heating speed ratio

$$\text{Electrically heated kettle} - \frac{1}{375^2} = 11,378$$

$$\text{Oil fired kettle} - \frac{1}{40^2} = 40.2$$

or the electrically heated kettle, due to the close spacing and arrangement of the heating surfaces will have a heating speed, other conditions being equal, 11,378 times that of the oil fired kettle.

Heating surface ratio

$$\text{Electrically heated kettle} = 49,500 \text{ square inches}$$

$$\text{Oil fired kettle} = 5,840 \text{ square inches} = 8.5$$

or the electrically heated kettle by reason of the greater area of heating surface exposed, will have a heating speed 8.5 times that of the oil fired kettle, or the electric kettle may be operated at the same speed as the oil fired kettle, but at a temperature difference between heating surface and oil of but 11.8% that of the oil fired kettle. The above heating speed and heating surface ratios may be readily increased to any desired degree by reducing the distance between adjacent turns of the spirals, and using a greater length of, or by increasing the width of the high resistance ribbons, thereby increasing the area of the heating surface.

Due to the arrangement of the heating surfaces in the electrically heated kettle, which creates a vigorous circulation of the oil uniformly through the spirals comprising the heating elements, the velocity flow of the oil in contact with the said heating surfaces, will, depending upon the viscosity of the oil, be from 10 to 25 times greater than in the oil fired kettle using the bot-

tom and lower sides only as the heating surface.

In the operation of the kettle, the oil being placed in the receptacle, the push button switch 6 is closed, causing the magnetic switch 56 to close and the electric heating current to pass by means of the main switch 55, the magnetic switch 56 and electrical connections to the electric heating elements comprising the ribbons 33 of high resistance metal, causing heat to be generated therein and transmitted to the oil that is in direct contact therewith. The oil circulating vigorously upwardly through the spirals comprising the heating elements and down the space between the outer edge of the spirals and the sides of the kettle, is quickly and uniformly heated to the desired degree.

If it is assumed that 1000 gallons of linseed is to be heated from a temperature of 60° F. to 585° F. and maintained thereat for a period of four hours to attain the desired viscosity, that at 560° an exothermic reaction occurs in the oil, causing a temperature rise of 20°, that there is required an electrical input at the rate of 300 kw. for 2 hours to raise the oil from 60 to 560°, that the electric energy required to supply radiation losses and maintain the oil at 585° is at the rate of 8 kw.

Therefore the thermostatic control switch 65 is set at 560° and when the temperature of the oil reaches that degree, thermostat will then act to open the magnetic switch 56 and to close the magnetic switch 58, the electric heating current then passing by means of the auto-transformer 57 or other suitable electric power reducing device, by way of the magnetic switch 58 to the heating elements in the kettle, being reduced by means of the auto-transformer to an electric capacity of slightly more than that required to maintain the oil at 585° or 10 kw. Due to the exothermic reaction mentioned above, the temperature of the oil will continue to rise to 585°, whereupon the thermostatic switch 63 will act to open the control circuit, causing the magnetic switch 58 to open and interrupt the electric heating current supplied resistance elements. Should the temperature of the oil become less than 585°, thermostatic switch 63 will act, causing magnetic switch 58 to close and supply the electric heating current to the heating elements, thus acting to maintain the oil in receptacle, accurately, at a determinate degree of heat.

It is desirable that the control system used to regulate the electric current supplied heating elements be so arranged as to avoid the frequent turning on and off of relatively large electric currents that may cause disturbance to the electric power supply system. In the preferred method of control hereinbefore described, the high electric capacity current of 300 kw. is turned on at the start of the heating period, and after the oil is heated to the desired temperature, the high electric current is disconnected by means of thermostatic control switch 65, thereafter the electric current required to regulate and maintain the oil at the desired degree of heat is supplied at the reduced rate of 10 kw. by means of auto-transformer or other suitable power reducing device.

Should the oil within receptacle be withdrawn at any time while the electric heating current is being supplied the heating elements, switch 62 actuated by float 63 will act to open magnetic switches 56 and 58 and interrupt the electric current supplied heating elements, thereby preventing the passage of electric heating current

through heating elements at all times except when they are immersed to a predetermined degree in the oil, so that accidental overheating of the heating elements is avoided.

5 It will be obvious that many other embodiments of the invention may be made by those skilled in the art and it will therefore be understood that the particular devices and arrangements and methods of use shown and described 10 herein are of an illustrative character and are not restrictive and that various changes in form, construction and arrangement of parts may be made within the spirit and scope of the following claims and such suitable electric current may 15 be employed whether direct, single, or polyphase alternating, as may be available and adapted to the particular requirement of the apparatus used.

Having thus described the invention, what I 20 claim is:

1. In a fluid heating apparatus, the combination of a receptacle for containing the fluid, a heating element consisting of a long narrow ribbon of high electrical resistance material wound 25 in a spiral having a diameter substantially greater than its width, means supporting the element substantially horizontally in the receptacle, and a source of electrical heating current connected to the element for heating the same.

30 2. In a fluid heating apparatus, the combination of a receptacle for containing the fluid, a plurality of heating elements each consisting of a long narrow ribbon of high electrical resistance material wound in a spiral having a diameter 35 substantially greater than its width, means supporting said elements substantially horizontally in the receptacle in vertically spaced relation, and a source of electrical heating current connected to said elements for heating the same.

40 3. In a fluid heating apparatus, the combination of a receptacle for containing the fluid, a heating element consisting of a long narrow ribbon of high electrical resistance material wound in a spiral having a diameter substantially 45 greater than its width, means supporting the element substantially horizontally in the receptacle, a source of electrical heating current connected to the element for heating the same, and means maintaining the level of the fluid in the receptacle substantially above the top of said element to insure thermosiphonic circulation of the fluid over both surfaces of the ribbon.

50 4. In a fluid heating apparatus, the combination of a receptacle for containing the fluid, a plurality of heating elements each consisting of a long narrow ribbon of high electrical resistance material wound in a spiral having a diameter substantially greater than its width, means supporting said elements substantially horizontally in the receptacle in vertically spaced relation, a source of electrical heating current connected to said elements for heating the same, and means maintaining the level of the fluid in the receptacle above the upper element to insure thermosiphonic circulation of the fluid over both surfaces of the ribbon.

55 5. A fluid heating apparatus comprising a fluid

containing receptacle, a plurality of electric heating elements comprising thin ribbons of high electrical resistance metal, edge supported in a closely spaced spiral form, in said receptacle and immersed in said fluid, means to cause the fluid to flow in a predetermined direction between said elements and in direct contact therewith, means for passing an electric heating current through said high resistance metallic ribbons, thermostatic means subject to the temperature of the fluid to selectively control the magnitude of the electric heating current passed through said heating elements, and thermostatic means subject to the influence of the temperature of the fluid to automatically control the supply of electric current to said electric heating elements.

6. A fluid heating apparatus comprising a fluid containing receptacle, a plurality of superimposed electric heating elements comprising thin ribbons of high electrical resistance metal, wound 20 in a closely spaced spiral form, means supporting said elements in superposed spaced relation in said receptacle and immersed in said fluid, means to cause the fluid to flow in a predetermined direction between said elements and in direct contact therewith, means for passing an electric heating current through said high resistance metallic ribbons, and automatic means operable by a predetermined minimum height of the fluid within said receptacle to disconnect the supply of 30 electric current to said elements.

7. A fluid heating apparatus comprising a fluid containing receptacle, a plurality of electric heating elements comprising thin ribbons of high electrical resistance metal, edge supported in a closely spaced horizontal spiral form, in said receptacle and immersed in said fluid, means to cause the fluid to flow in a predetermined direction between said elements and in direct contact therewith, means for passing an electric heating current through said high resistance metallic ribbons, thermostatic means subject to the temperature of the fluid to selectively control the magnitude of the electric heating current passed through said heating elements, thermostatic means subject to the influence of the temperature of the fluid to automatically control the supply of electric current to said electric heating elements and automatic means operable by the height of the fluid within said receptacle to control the supply of electric current to said elements.

8. A fluid heating apparatus comprising a fluid containing receptacle, having an inlet and an outlet, a plurality of electric heating elements comprising closely spaced spirals of relatively narrow metallic ribbons of high electrical resistance wound in spiral form, means supporting said elements transversely, one above the other within said receptacle and immersed in said fluid, means for passing an electric heating current through said high resistance metallic ribbons, means for causing the fluid to flow uniformly between said heating elements and in direct contact therewith.

65 ROBERT A. CARLETON.
